UNITED STATES PATENT OFFICE.

JAMES MAZZOCO, OF GALLUP, NEW MEXICO, ASSIGNOR OF ONE-HALF TO FRED MUTTO, OF GALLUP, NEW MEXICO.

BEET-TOPPING MACHINE.

Application filed January 8, 1923. Serial No. 610,512.

To all whom it may concern:

Be it known that I, JAMES MAZZOCO, a citizen of the United States, residing at Gallup, in the county of McKinley and State of New Mexico, have invented new and useful Improvements in Beet-Topping Machines, of which the following is a specification.

This invention relates to improvements in beet topping machines and has for an object the provision of a machine whereby the tops of beets standing in a field may be uniformly, properly, quickly and effectively removed, preparatory to harvesting the beets.

Another object of this invention is to be found in the provision of a novel form of cutting element for simulating hand operation in removing the beet tops, together with means for operating said element, whereby the tops may be removed without injury to the beets.

Another object of the invention is to be found in the provision of means for regulating the position of the cutting element altitudinally with respect to the beets, whereby the latter may be topped evenly and the cutting element be prevented from undesirable cutting into the beets or digging into the ground.

Another object of the invention is to be found in the provision of means whereby position regulating means for the cutting element may be mounted yieldingly and adjustably to accommodate said cutting element to the altitude or position of the crown of a beet.

A further object of the invention is to be found in the provision of means whereby the beet tops may be displaced laterally after each cutting operation, so that the operation of topping succeeding beets will not thereby be interrupted nor obstructed.

Another object of this invention is to provide means for combing or bisecting or intersecting the tops of standing beets in a field in order to contact an altitudinally adjusting element with the crowns of succeeding beets and thereby control the altitude of a cutting element adapted to remove said tops and crowns progressively and uniformly.

Another object of this invention is to provide a swiftly moving cutting element, adapted to simulate hand work in cleanly and quickly beheading or "topping" any

standing beet coincident with the engagement with the crown thereof of an altitudinally adjusting element controlling the altitude of the cutting element.

A further object of this invention is to combine, in a single machine or implement three elements, viz; an altitudinally adjusting device adapted to comb or bisect or intersect the tops of standing beets and engage the crowns thereof successively; a swiftly moving cutting element, simulating hand work, adapted to follow the adjusting element and cleanly and quickly behead or "top" successive beets; and a floating frame common to both elements and adapted to apply the altitudinal adjustment of the first element to the cutting element.

With the above and other objects in view, the invention consists of novel features of combination and details of construction, hereinafter more fully described, illustrated in the accompanying drawings and pointed out in the appended claims.

In the drawings:

Figure 1 is a top plan view of a beet topping machine embodying my invention. Figure 2 is a side elevation of the same partly in section. Figure 3 is a transverse section taken substantially on the line 3-3 of Figure 2. Figure 4 is a section taken substantially on the line 4-4 of Figure 1. Figure 5 is a detail plan view of the cutting element or revolving knife. Figure 6 is a similar view of one form of the altitudinally adjusting element.

Figure 7 is a fragmentary side elevation illustrating a modified form of the invention. Figure 8 is a detail view of the modified form of the altitudinally adjusting element enlarged and at right angles to the 95 showing in Figure 7. Figure 9 is a section on the line 9-9 of Figure 8.

Figure 10 is a fragmentary view illustrating a modified form of cutting element and top displacer. Figure 11 is a detail plan view of the elements of Figure 10.

Figure 12 is a fragmentary plan view showing another modified form of cutting element.

Referring to the drawings in detail, 105 wherein like characters of reference denote corresponding parts, the machine is shown as comprising a land vehicle having a main frame 15 supported on a rear axle 16 and a front axle 17, the latter having steering 110

knuckles 18 pivotally mounted at each end thereof. The steering knuckles 18 are connected by rods 19 with a tongue 20, the latter being pivotally mounted as shown at 5 21 on the front axle 17. By reference to Figure 1 of the drawing it will be seen that when the tongue is pivotally moved, the front wheels 22 will likewise be moved, so that the machine will follow the line of 10 draft.

The rear wheels 23 provide traction for certain operating elements and together with the wheels 22 are capable of lateral relative adjustment. For this purpose both the axles 15 16 and 17 extend an appreciable distance beyond the sides of the frame 15, the purpose being to space the wheels on the axles in accordance with the width between rows 20 of standing beets in a field. The wheels are held in adjusted position by collars 24 on the axles and the rear wheels further are splined on the axle 16 so that said axle will be rotated thereby.

The main frame 15 includes a rear transverse bar 25 and an upwardly arched front transverse bar 26. A supplemental or floating frame 28 is hinged at one end to the bar 25, by hinges 27, and extends within the arch of the bar 26. The frame 28 is susceptible of vertical movement through an arc. Hanger rods 29 threaded in their lower portions are mounted in and depend from the arch of the bar 26. A hanger bar 30, forming a front transverse end of the supplemental or floating frame 28 is slidably mounted on the rods 29 and springs 31 are mounted on the rods beneath and yieldingly support said hanger bar 30. These springs are carried by adjusting nuts 32 threaded on the 40 lower ends of the rods. The forward end of the supplemental frame 28 may thus be moved through an upward arc and is yieldingly supported upon the springs 31, its normal position being adjusted through the 45 medium of the adjusting nuts 32, which are mounted below and limit downward movement of said frame.

The supplemental frame 28 has depending therefrom a substantially U-shaped bearing 50 yoke 33, and mounted in bearings carried by this yoke is a vertically disposed shaft 34, said shaft being susceptible of vertical adjustment. Mounted on the lower end of the shaft 34 is a cutting element 35 or revolving knife, which includes oppositely extending radial blades 36 and oppositely extending clearing or scavenging arms 37, the latter being disposed substantially at right angles to the blades 36. The cutting element or 55 revolving knife is adapted to be rotated by the operation of the shaft 34, so that the blades 36 will cut the tops of the beets, the horizontal position of these blades being manually determined in the first instance by 60 adjustment of the shaft 34. This adjust-

ment is effected by means of collars 38 which serve to hold the shaft against longitudinal movement.

The shaft 34 is driven from the wheels 23 and for this purpose there is splined on the 70 upper end of this shaft a pinion 39, which is engaged and driven by a gear 40 of larger diameter than the pinion. The gear 40 is rigidly mounted on a horizontally disposed shaft 41, mounted in suitable bearings provided in the supplemental or floating frame 28, and rigidly mounted on the shaft 41 is a sprocket wheel 42. The wheel 42 is driven from a sprocket wheel 43, of larger diameter than the first sprocket, fixed on the rear 80 axle 16, through a sprocket chain 44. The relative sizes of the sprocket wheels 42 and 43 and the gears 39 and 40 provide for a rapid rotation or high speed of the cutting element 35 relative to the R. P. M. of the 85 traction wheels, the speed of said cutting element being substantially 800 R. P. M. Since the supplemental or floating frame 28 is hingedly mounted on the main frame an automatic chain tightener in the form of a 90 roller 45 is carried on the outer end of an arm 46 pivoted on a part of the main frame and is yieldingly held in engagement with the chain by a spring 47 further connecting said arm and frame, so that the 95 chain will be maintained at the proper tautness to drive the shaft 34, irrespective of the relative positions of the frames 15 and 28.

The bearing yoke 33 is braced by means of longitudinal and transverse braces 48 100 and 49.

Various means may be employed for contact with the beets to facilitate the topping operation, one of such means being illustrated in detail in Figure 6. This means comprises an altitudinally adjusting member which includes a frame 50 and spaced longitudinally disposed curved parallel rods 51. This member is located in advance of the cutting element and its rear end is flexibly and pivotally supported by hanger rods 52 which have their upper ends mounted in eyes carried by the supplemental or floating frame 28 and their lower ends engaging in eyes carried by the frame 50. The frame 50 and rods 51 are curved forwardly and upwardly and the forward end of the frame is supported by adjustable hanger rods 53 pivotally secured at each side to the frame, which rods extend through parallel bearing sleeves 54 pivoted to the side bars of the supplemental or floating frame 28 as shown at 55. The upper ends of the rods 53 are threaded and adjusting nuts 56 are screwed thereon and bear on the ends of the sleeves 54, whereby the forward end of the altitudinally adjusting member may be vertically adjusted within an arcuate range of movement.

Owing to the flexible and pivotal connec-

tion of the rods 52 with the floating frame 28 and altitudinally adjusting member, the latter member has some freedom of lateral vibration, permitting it to comb through, 5 bisect and intersect the beet tops and cause the lower faces of some of the rods 51 to contact with the crowns of successive beets irrespective of the altitude of said crowns.

As the machine travels along and over a 10 row of beets, the tops will enter between some two or more of the rods 51 and the rods so combing or intersecting the tops will engage the crowns of the beets successively and be supported and altitudinally adjusted 15 thereby, the altitudinal adjustment being communicated through the hanger rods 52 and 53 to an arcuate adjustment of the floating frame 28 and corresponding vertical adjustment of the cutting element so that the 20 blades of the cutting element will horizontally strike and bisect the crowns of the beets at substantially the same plane on the beet relative to the apex of the crown, irrespective of their position above the ground 25 and will remove the tops and a segment of each crown slightly below the lowermost point of the contacting rods. After the cutting element has operated to remove the top and segment, an arm 37 following the blade 36 will strike the segment or depending portion of the top and knock the same to one side out of the path of the next succeeding blade 36 of the cutting element, so that the 30 operation of topping the next succeeding beet will not be interfered with, interrupted 35 or obstructed.

It will be observed that the amount of the segment or crown removed may be regulated primarily through an adjustment of the cutting element 35, while the altitudinally adjusting member may rise through contact of the rods 51 with the beets in the event that some of the beets extend upward above the majority in the row, the springs 31 being 40 so tensioned and adjusted by the nuts 32 as to support the forward end of the supplemental or floating frame 28 in a manner to permit the same to rise without requiring that its entire weight be lifted by contact of the altitudinally adjusting member 45 with the crown of a beet.

In Figures 7, 8 and 9 there is illustrated 50 a different form of altitudinally-adjusting member which includes spaced disks 57. These disks are carried by a transverse shaft 58 whose opposite ends are mounted 55 in bearing members 59, the latter being supported by hanger rods 60 and 61. The rods 60 have their upper ends supported in eyes 60 carried by the supplemental floating frame 28, while the rods 61 pass through the bearing sleeves 54 previously described, said sleeves being susceptible of pivotal adjustment upon the bolts 55. The height of the 65 disks 57 may be adjusted and maintained in

adjusted position by means of nuts 62. The disks 57 are provided with openings 63 for the passage of the shaft 58, said openings being of a greater diameter than the shaft, so that said disks may be moved relatively 70 as indicated by the dotted lines in Figure 9 and thus prevent injury to the beets. The disks 57 are spaced apart by means of spacing sleeves 64.

In Figures 10 and 11 there is illustrated a 75 modified form of cutting element, which is shown in the form of a blade 65 which extends forwardly from the bearing yoke 33. In this form of the invention, the shaft 34 has secured thereon oppositely extending 80 curved arms 66 which move horizontally over the top of the blade 65 and act to displace the severed top of the beet after the manner of the arms 37.

In Figure 12 there is illustrated still a 85 different form of cutting blade. This blade which is indicated at 67 is provided with a substantially V-shaped notch 68 whose edges define cutting edges, so that as the beet top enters this V-shaped notch during the forward movement of the machine, the said top 90 will be removed by a shearing action.

The invention is susceptible of various 95 changes in its form, proportions and minor details of construction and the right is herein reserved to make such changes as properly fall within the scope of the appended claims.

I claim as my invention—

1. A beet topping machine embodying a 100 main frame, wheels supporting the frame, a vertically-movable supplemental floating frame carried by the main frame, a device depending from and carried by the supplemental frame, a shaft vertically disposed and mounted for rotation in said device, means for rotating said shaft, a cutting element 105 horizontally disposed on said vertical shaft, and yieldingly-mounted substantially horizontally-disposed altitudinally-guiding elements connected with said supplemental frame, said altitudinally-guiding elements being located in advance of the cutting element and adapted to engage the crowns of beets for regulating the plane of contact of the cutting element with the beets during 110 the cutting operation.

2. A beet topping machine embodying a 115 main frame, wheels supporting the frame, a supplemental floating frame having one end hingedly secured to the main frame, means for yieldingly supporting the opposite end of the supplemental frame, whereby the latter may be moved vertically, a device depending from and carried by the supplemental frame, a shaft vertically disposed and mounted for rotation in said device, means for rotating said shaft, and a cutting element 120 carried by said vertical shaft, together with spaced means carried by the supplemental frame in advance of the cutting element, said 125

spaced means being adapted to engage the crowns of beets for regulating the altitudinal position of the cutting element.

3. A beet-topping machine embodying a main frame, a vertically movable supplemental floating frame carried thereby, a device depending from and carried by the supplemental frame, a shaft vertically disposed and mounted for rotation in said device, means for rotating said shaft, a cutting element horizontally disposed on said shaft and means for yieldingly and adjustably supporting the supplemental frame to regulate the altitudinal position of the cutting element.

4. A beet-topping machine embodying a main frame, a vertically movable supplemental floating frame carried thereby, a device depending from and carried by the supplemental frame, a shaft vertically disposed and mounted for rotation in said device, means for rotating said shaft, a cutting element horizontally disposed on said shaft, scavenging means carried by said shaft and operable after each cutting operation to displace the severed beet tops, means for yieldingly and adjustably supporting the supplemental frame to regulate the altitudinal position of the cutting element and scavenging means and means for adjusting the altitude of the scavenging means and the cutting element on said shaft.

5. A beet topping machine embodying a main frame, a vertically movable supplemental floating frame carried thereby, a substantially U-shaped bearing yoke carried by the supplemental frame, a vertically disposed shaft mounted for rotation in said yoke, means whereby the shaft may be rotated, a horizontally disposed cutting element mounted on the shaft, and means for yieldingly and adjustably supporting the supplemental frame to regulate the altitudinal position of the cutting element.

6. A beet-topping machine embodying a main frame, a vertically movable supplemental floating frame carried thereby, a supporting device depending from and carried by the supplemental frame, a shaft vertically disposed and vertically adjustable in said device, means for rotating said shaft, a cutting element horizontally disposed on said shaft beneath said device, means for yieldingly and adjustably supporting the supplemental frame auxiliary to its primary support on the main frame, a substantially rectangular frame curved longitudinally and disposed beneath the supplemental frame, hangers adjustably and flexibly connecting the forward end of said rectangular frame to said supplemental frame, means for flexibly connecting the rear portion of the rectangular frame to the supplemental frame, the latter means serving as a fulcrum for the rectangular frame, and spaced bars

in and carried rigidly by said rectangular frame, said spaced bars being curved longitudinally.

7. A beet topping machine embodying a frame, wheels supporting the frame, a vertically movable topping element and combined means composed of a curved frame pivotally and flexibly supported at its rear end adjacent to the topping element and adjustably supported at its forward end and, located in advance of the topping element together with curved spaced bars in and rigidly carried by said curved frame for combining through the tops of the beets, engaging the crowns thereof and thereby regulating the altitudinal adjustment of the topping element.

8. A beet-topping machine embodying a frame, wheels supporting said frame, a relatively movable supplemental frame having one end hingedly secured to the main frame, an upwardly arched yoke on the main frame extending across the forward end portion of the supplemental frame, hangers depending from said yoke and extending loosely through the front end bar of the supplemental frame, expansive coil springs on said hangers below said bar, adjusting means on said hangers below said springs, together with a cutting element carried by the supplemental frame and means also carried by the supplemental frame in advance of the cutting element for supporting and altitudinally guiding said cutting element from and relative to the crowns of the beets during the topping operation.

9. A beet topping machine embodying a frame, wheels supporting the frame, a relatively movable supplemental frame having one end hingedly secured to the main frame, means for yieldingly supporting the opposite end of the supplemental frame whereby said frame may be moved through an arc vertically, said means including a yieldingly supported hanger bar, together with a cutting element carried by the supplemental frame and means also carried by the supplemental frame in advance of the cutting element for supporting and altitudinally guiding said cutting element from and relative to the crowns of the beets during the topping operation.

10. A beet topping machine embodying a frame, wheels supporting the frame, a relatively movable supplemental frame having one end hingedly secured to the main frame, means for yieldingly supporting the opposite end of the supplemental frame, whereby said frame may be moved through an arc vertically, said means including vertically disposed hanger rods carried by the main frame, a hanger bar mounted on and movable vertically of the rods and springs carried by the rods and supporting the hanger bar together with a cutting element carried

by the supplemental frame and means also carried by the supplemental frame in advance of the cutting element for passing through the tops of the beets and over the 5 crowns thereof to altitudinally adjust the plane of contact of the cutting element with the crowns of the beets.

11. In a beet-topping machine a cutting element mounted for rotary travel on a horizontal plane, a top-scavenging element mounted for rotation with said cutting element, and means for driving said elements conjunctively at substantially 800 R. P. M.

12. In a beet-topping machine a cutting element composed of a knife having a curved edge, said knife being mounted in radial relation to a driving means and adapted to be driven at relatively high speed adapted to simulate hand work and an altitudinally adjusting member adapted to comb through the tops and engage the crowns of beets, whereby the plane of contact of the cutting element with said beets is adjusted and determined.

13. In a beet-topping machine a high speed (substantially 800 R. P. M.) radially-ar-

ranged rotary cutting element having curved cutting edges eccentric to the axis of rotation of the element adapted to simulate hand work and adapted to decrown beets successively, and an altitudinally adjusting member adapted to comb through the tops and engage the crowns of beets, whereby the plane of contact of the cutting element with said beets is adjusted and determined.

14. In a beet topping machine, a knife 35 mounted for rotary travel around an axis, said knife being formed with a cutting edge eccentric to said axis and means for driving said knife at relatively high-speed simulating hand work.

15. In a beet topping machine, a radial knife, as contradistinguished to a disc, said knife being formed with cutting edges eccentric to its axis, on similar parabolic curves and opposite to each other and means for 45 driving said knife at relatively high-speed simulating hand work.

In testimony whereof I affix my signature.

JAMES MAZZOCO.
